US00D573186S

(12) **United States Design Patent**
Rommel

(10) **Patent No.:** **US D573,186 S**
(45) **Date of Patent:** **** Jul. 15, 2008**

(54) **WRITING INSTRUMENT WITH BOW
OPERATOR**

(75) Inventor: **Volkmar Rommel**,
Schwaebisch-Gmuend (DE)

(73) Assignee: **Senator GmbH & Co KGaA**, Gross
Bieberau (DE)

(**) Term: **14 Years**

(21) Appl. No.: **29/265,959**

(22) Filed: **Sep. 12, 2006**

Related U.S. Application Data

(63) Continuation of application No. 29/201,309, filed on
Mar. 12, 2004, now abandoned.

(30) **Foreign Application Priority Data**

Sep. 12, 2003 (DE) 403 06 002

(51) **LOC (8) Cl.** **19-06**

(52) **U.S. Cl.** **D19/51**

(57) **CLAIM**

The ornamental design for a writing instrument with bow
operator, as shown and described.

DESCRIPTION

FIG. 1 is a rear elevation view of the writing instrument with
bow operator showing my new design;

FIG. 2 is a side elevation view thereof;

FIG. 3 is a front elevation view thereof;

FIG. 4 is a side elevation view thereof;

FIG. 5 is a top view thereof; and,

FIG. 6 is a bottom view thereof.

1 Claim, 1 Drawing Sheet
